UNITED STATES PATENT OFFICE.

GEORGE ALBERT LYON, OF PHILADELPHIA, PENNSYLVANIA.

AUTOMOBILE-BUFFER.

1,325,729.

Specification of Letters Patent. Patented Dec. 23, 1919.

Application filed May 22, 1917. Serial No. 170,130.

To all whom it may concern:

Be it known that I, GEORGE ALBERT LYON, a citizen of the United States, and resident of Philadelphia, Philadelphia county, 5 Pennsylvania, have made a certain new and useful Invention Relating to Automobile-Buffers, of which the following is a specification, taken in connection with the accompanying drawing, which forms part of the 10 same.

This invention relates especially to buffers for automobiles or other vehicles which may be conveniently formed of vertically rigid and horizontally yielding members, 15 such as spring steel strips, which are concentrically curved at theirlapping connecting portions so that they may be more securely connected while permitting the desired adjustability. The forward or impact receiving members of the buffer are also preferably forwardly bowed and uniformly curved throughout and special connecting devices may be used for adjustably connecting these parts.

25 In the accompanying drawing showing in a somewhat diagrammatic way illustrative embodiments of this invention,

Figure 1 is a top view showing one embodiment;

30 Fig. 2 is a similar view showing another form;

Fig. 3 is an enlarged top view showing the end connections; and

Fig. 4 is a partial front view showing a 35 connector device.

The front or impact receiving member of the buffer may preferably be formed of one or more vertically rigid and horizontally yielding members, such as spring steel strips 40 having six or eight times as great a vertical width as their thickness in a horizontal direction, and these front strips where they are connected together and also any other members connected thereto are preferably 45 formed as concentric curves throughout these lapping contacts which allows the lateral adjustment of the parts and makes it easy to firmly and reliably connect them in position. If desired, the front members 50 may be forwardly bowed and uniformly curved throughout which gives a greater extent of resilient yielding action under collision conditions. If desired also these front members may overlap at their central 55 portion so as to render this impact receiving member of the buffer of adjustable width

which is desirable in some cases. The front strip 4 forming this impact receiving member of the buffer may have one projecting end 5 while its other end 6 may be secured to the rear impact receiving strip or member 3 adjacent its projecting end 7. The attaching members 1, 2 may be formed of similar vertically rigid spring strip and preferably have their forward ends outwardly curved and formed with curved lapping portions 8 formed substantially concentric with the adjacent parts of the front member of the buffer so as to facilitate connection therewith. If desired this part 8

may extend out to or adjacent the extreme end of the impact receiving member of the buffer and be closely secured to the other buffer members by any suitable connecting devices or clips, these strips being shown in Fig. 1, as somewhat separated for greater clearness, although the details of the connection and arrangement of this part of the device are shown more clearly in Fig. 3. The connecting clips may, if desired, be ar-

ranged with diagonally projecting clip ends 28 brought together and held as by a suitable screw or bolt 29 which clamps the enclosed strips together in two directions as shown and explained in greater detail in 85 Lyon patent 1,198,246, of September 12, 1916. It is also desirable to have these connecting clips formed with suitable retainer devices so as to positively hold them in desired position on one of the connected members. For this purpose the clip 13 may, as indicated, be formed with an integral or other retainer lug 27 adapted to loosely fit into a retainer hole 32 formed in one of the buffer members, such as 8, so that the 90 clip is thereby held in desired longitudinal position on this member. In assembling the device the clip is first slipped over this member and the lug forced into the hole while the clip is in its relatively open released position. Then the other member 7 may be slipped endwise into the clip which on tightening securely holds these parts together. A similar clip may be used to secure together the other ends 5 and 9 of the 95 buffer front members which are of course in direct close contact throughout their connecting portions. The two impact receiving members may be conveniently connected by suitable U-bolt connectors 11, 12, preferably coöperating with holes in the bifurcated or split end members 23 formed on

90

100

110

one or both of these strips. As shown in Fig. 4 these split ends of the strip 6 may be forced out laterally and formed with suitable holes 24 to accommodate the U-bolt 12 and in this way the connector is held in longitudinal alinement with one of the members while tightly holding them together as by suitable nuts 26 and the connector plate 23, if desired. It is further understood that legs of the U-bolts are spaced just far enough apart to be brought into close engagement when tightened with the edges of the connected strips so as to thus hold them against vertical movement. It is, of course, understood that such alining or bifurcated ends may be arranged on any of the strips to be connected together either on one of the outer strips 6 as shown in Figs. 1, 3 and 4, or on one of the inner strip ends 10 where the device has a similar alining holding action. In this case, of course, the attaching member 1 has a part of its forward portion concentrically curved so as to be parallel and in close contact with this adjacent buffer member 10, while the extreme end 9 of this attaching member is preferably brought over into close engagement with the end 5 of the front member so as to be directly held in contact therewith. This arrangement makes it easy to laterally adjust the buffer strips, since the strips 3, 4 may, for example, be slipped together to the extent of several inches without noticeably or undesirably affecting the curve of the front impact receiving member. Such an adjustment may be resorted to to bring the attaching members somewhat closer together or these attaching members may be independently adjusted, if desired, after the desired buffer width has been secured by regulating the position of the twolapping front members.

In the arrangement shown in Fig. 2, a single front or impact receiving member 14 is shown. This spring strip member may be outwardly bowed and be uniformly curved so that its projecting ends 17, 18 may, if desired, have the same curvature as the central part of this member. The rearwardly extending attaching members 15, 16 are preferably forwardly and outwardly curved and provided with connecting portions 19, 20, curved so as to be substantially concentric with the adjacent portions of the front or impact receiving member to which they may be connected in any suitable way. Retainer clips 21, 22, may be used for this purpose and may coöperate with one or more retainer holes, such as 30, 31, in the ends of these attaching members. In this way the clips are positively held upon the attaching members so that they are always in position to be tightened and securely hold the parts against vertical movement.

65 This invention has been described in con-

nection with a number of illustrative embodiments, forms, proportions, parts, arrangements, materials, method of connection and use, to the details of which disclosure the invention is not of course to be limited, since what is claimed as new and what is desired to be secured by Letters Patent is set forth in the appended claims:

1. An automobile buffer comprising two forwardly bowed impact receiving members of uniform curvature and formed of vertically rigid flat spring steel strips overlapping to reinforce the central portion of the buffer, vertically rigid spring strip attaching members adapted to be connected to a vehicle frame and formed with forwardly and outwardly curved portions having connecting ends formed with substantially the same curvature as the adjacent parts of said impact receiving members, retainer clip connectors connecting the ends of said attaching members and impact receiving members and each formed with a retainer lug engaging a retainer hole adjacent the end of one of said members, U-bolt connectors connecting the doubled lapping portions of said impact receiving members to said attaching members and each held in longitudinal alinement with respect to one of said members by passing through a perforated bifurcated end of one of said strips to closely engage the edges of the other connected strips and hold them in substantial vertical alinement. 95

2. An automobile buffer comprising two forwardly bowed impact receiving members formed of vertically rigid flat spring steel strips overlapping to reinforce the central portion of the buffer, vertically rigid spring strip attaching members adapted to be connected to a vehicle frame and formed with forwardly and outwardly curved portions having connecting ends formed with substantially the same curvature as the adjacent parts of said impact receiving members, and connectors connecting the ends of said attaching members and impact receiving members and the doubled lapping portions of said impact receiving members to said attaching members. 110

3. An automobile buffer comprising two overlapping forwardly bowed impact receiving members of uniform curvature and formed of vertically rigid flat spring steel strips overlapping to reinforce the central portion of the buffer, vertically rigid spring strip attaching members adapted to be connected to a vehicle frame and formed with forwardly and outwardly curved portions having connecting ends formed with substantially the same curvature as the impact receiving members and lapping and reinforcing said impact receiving members at the ends of the buffer and connectors comprising retainer clip connectors connecting 125

130

the ends of said attaching members and impact receiving members and each formed with a retainer lug engaging a retainer hole adjacent the end of each of said attaching members.

4. An automobile buffer comprising two overlapping forwardly bowed impact receiving members formed of vertically rigid flat spring steel strips overlapping to reinforce the central portion of the buffer, vertically rigid spring strip attaching members adapted to be connected to a vehicle frame and formed with forwardly and outwardly curved portions having connecting ends formed with substantially the same curvature as the impact receiving members and lapping and reinforcing said impact receiving members at the ends of the buffers and connectors comprising retainer clip connectors and each formed with a retainer lug engaging a retainer hole in said members.

5. An automobile buffer comprising a forwardly bowed impact receiving member formed of vertically rigid flat spring steel strip overlapping to reinforce the central portion of the buffer, vertically rigid spring strip attaching members adapted to be connected to a vehicle frame and formed with forwardly and outwardly curved portions having connecting ends formed with substantially the same curvature as the impact receiving members to form concentric lapping contact portions and connectors adjustably connecting said lapping contact portions.

6. An automobile buffer comprising a forwardly bowed impact receiving member formed of vertically rigid flat spring steel strip, vertically rigid spring strip attaching members adapted to be connected to a vehicle frame and having connecting ends formed with substantially the same curvature as the impact receiving members to form concentric lapping contact portions and connectors adjustably connecting said lapping contact portions.

7. An automobile buffer comprising overlapping spring strip members and retainer clip connectors clamping together the ends of said members and each formed with a retainer lug engaging a retainer hole adjacent the end of one of said members.

8. An automobile buffer comprising overlapping spring strip members and retainer clip connectors clamping together said members and each formed with a retainer engaging a retainer hole in one of said members.

9. An automobile buffer comprising overlapping spring strip members and U-bolt connectors connecting said members and

each held in longitudinal alinement with respect to one of said members by passing through a perforated bifurcated end of one of said strips to closely engage the edges of the other connected strips and hold them in substantial vertical alinement.

10. An automobile buffer comprising overlapping spring strip members and U-bolt connectors connecting said members and each held in longitudinal alinement with respect to one of said members by passing through a perforated bifurcated end of one of said strips to pass around the edges of the other connected strips.

11. An automobile buffer comprising overlapping strip members and bolt connectors connecting said members and held in longitudinal alinement with respect to one of said members by passing through a perforated laterally extended portion of one of said strips to pass around the edges of the other connected strips.

12. An automobile buffer comprising a forwardly bowed impact receiving member formed of vertically rigid flat resilient strip, vertically rigid resilient strip attaching members adapted to be connected to a vehicle frame and having connecting portions curved to conform to the coöperating portions of said impact receiving member and formed with retainer holes adjacent the ends of said attaching members to form lapping contact portions and connectors having retainer lugs to coöperate with said retainer holes and connecting said lapping contact portions.

13. An automobile buffer comprising a forwardly bowed impact receiving member formed of vertically rigid flat resilient strip, resilient strip attaching members, adapted to be connected to a vehicle frame and having connecting portions curved to conform to the coöperating portions of said impact receiving member to form lapping contact portions and connectors adjustably connecting said lapping contact portions.

14. An automobile buffer comprising overlapping resilient strip members and retainer clip connectors clamping said members together and having an adjustable closed contour outline and a substantially rectangular opening to accommodate said members, said connectors each being formed with an inwardly projecting retainer lug engaging a retainer hole adjacent the end of one of the connected members.
